UNITED STATES PATENT OFFICE.

WILLIAM HENRY BARR, OF STEUBENVILLE, OHIO, ASSIGNOR TO ALEXANDER J. BEATTY & SONS, OF SAME PLACE.

DESIGN FOR A JAR.

SPECIFICATION forming part of Design No. 18,224, dated April 3, 1888.

Application filed January 12, 1888. Serial No. 200,581. Term of patent 3½ years.

To all whom it may concern:

Be it known that I, WILLIAM HENRY BARR, a citizen of the United States, residing at Steubenville, in the county of Jefferson and State of Ohio, have invented and produced a new and original Design for Glassware; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This design relates to the ornamentation of all articles of glassware, and for convenience is illustrated upon a jar or mug, as shown in the accompanying drawings, forming a part of this specification, in which—

Figure 1 is a side elevation, and Fig. 2 a cross-section on the line X X of Fig. 1.

The design consists in checked bars or ribs on the body of the article, said checked ribs or bars being of any contrasting color with the body of the article. These ribs or bars extend vertically in parallel rows around the body of the article and in horizontal rings or bands, which intersect with the vertical bars, forming the checked surface.

The body A of the jar is provided with the ribs or bars B and C, which are of contrasting color therewith. The bars or ribs B are arranged in parallel rows about the jar and extend flush from the top edge thereof to the bottom, where they turn under and form supports for the jar. The bars or ribs C encircle the jar and form rings or bands at different levels which intersect with the vertical ribs or bars B.

Having thus described my invention, what I claim, and desire to secure by Letters Patent, is—

The herein shown and described design for a jar or kindred article of glassware, consisting of vertical and horizontal ribs of contrasting color with the body of the jar, the vertical ribs intersecting with the horizontal ribs to form a checked appearance.

In testimony whereof I affix my signature in presence of two witnesses.

WILLIAM HENRY BARR.

Witnesses:

GEORGE BEATTY,
P. E. BRADY.
